CLAIM

The ornamental design for the combined sunglasses and band, as shown and described.

DESCRIPTION

FIG. 1 is a front perspective view of the combined sunglasses and band showing my new design with the resilient, fabric encased, head encircling, two part band in its unstretched unfastened configuration;

FIG. 2 is a front perspective view similar to FIG. 1 with the resilient, fabric encased, head encircling, two part band in a fastened, somewhat stretched configuration;

FIG. 3 is a front elevation view thereof;

FIG. 4 is a rear elevation view thereof;

FIG. 5 is a top plan view thereof;

FIG. 6 is a right side elevational view thereof;

FIG. 7 is a bottom plan view thereof; and,

FIG. 8 is a left side elevational view of the sunglasses and band in accordance with my new design.

FIG. 1

FIG. 2

FIG. 3

FIG. 4

FIG. 5

FIG. 6

FIG. 7

FIG. 8
